UNITED STATES PATENT OFFICE.

PAUL C. WHALEY, OF MOUNTAIN VIEW, CALIFORNIA.

DESIGN FOR A RADIATOR-EMBLEM.

52,420.

Specification for Design.

Patented Sept. 10, 1918.

Application filed May 9, 1916. Serial No. 96,452. Term of patent 14 years.

To all whom it may concern:

Be it known that I, PAUL C. WHALEY, a citizen of the United States, residing at Mountain View, in the county of Santa Clara and State of California, have invented a new, original, and ornamental Design for Radiator-Emblems, of which the following is a specification, reference being had to the accompanying drawing, forming a part thereof.

The figure is a perspective view of a radiator emblem, showing my new design.

I claim:

The ornamental design for a radiator emblem, as shown.

PAUL C. WHALEY.

Witnesses:

WILBUR L. CAMP,
O. W. DALY.
